(57) **CLAIM**

The ornamental design for a paddle shifter, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a paddle shifter showing my new design;

FIG. 2 is a front and left side perspective view thereof;

FIG. 3 is a rear and left side perspective view thereof;

FIG. 4 is a right side elevation view thereof;

FIG. 5 is a left side elevation view thereof;

FIG. 6 is a rear elevation view thereof;

FIG. 7 is a top plan view thereof; and,

FIG. 8 is a bottom plan view thereof.

The broken lines showing portions of the paddle shifter form no part of the claimed design.

1 Claim, 8 Drawing Sheets
